UNITED STATES PATENT OFFICE.

JAMES A. NOLAN, OF BOWERSTON, OHIO.

MINE-CAR CAGER.

1,362,958.

Specification of Letters Patent. Patented Dec. 21, 1920.

Application filed September 1, 1920. Serial No. 407,459.

To all whom it may concern:

Be it known that I, JAMES A. NOLAN, a citizen of the United States, residing at Bowerston, in the county of Harrison and 5 State of Ohio, have invented certain new and useful Improvements in Mine-Car Cagers, of which the following is a specification.

This invention relates to means designed more particularly to automatically feed 10 mine cars on elevator platforms or cages and to dumps as used in mines or any place for handling coal or other minerals.

The main object of this invention is to provide any desired amount of cushioning 15 for the stops, so that cars may be fed to the cage or dump with great rapidity, without damage or severe shocks to the cars. This I desire to accomplish by means of a 20 cross head or base plate, on which the car stops are permanently located in such a manner as to keep them adjacent to the rails and in a position to hold the trip of cars. Any style of crosshead may be used which 25 travels parallel to the rails and may be cushioned by means of springs, weights, compressed air or liquids, or by any other method known to the art. Another object is to provide means for automatically feeding 30 cars to a cage or dump in which means the operation of the cage and the motion of the cars are used to operate the device.

In the drawings:

Figure 1 is a plan view of my preferred construction showing the entire mechanism 35 as used in connection with an elevator cage.

Fig. 2 is a sectional side elevation of Fig. 1.

Fig. 3 is an enlarged end view of Fig. 1, looking in the direction of the elevator cage.

Fig. 4 is an enlarged view in cross section, 40 showing the preferred construction of the bumper springs.

Fig. 5 is a side view corresponding to Fig. 4.

Fig. 6 is an enlarged side elevation showing the preferred method of mounting the 45 car-stops.

Fig. 7 is a side view of Fig. 6 showing the car-stops in their closed and open position.

Fig. 8 is a diagrammatic view showing 50 the method of holding the car-stops operating means in either the open or closed position.

Fig. 9 is a plan view of a modified construction of the bumper spring.

55 Fig. 10 is a side elevation of Fig. 9.

Fig. 11 is a diagrammatic representation

of the car-stops operating means showing the car-stops in their closed position.

Fig. 12 is another diagrammatic representation of the car-stops operating means 60 showing the car-stops in their open position.

Fig. 13 is a front elevation of the so-called tripping member secured to the elevator platform.

This invention is especially intended as an 65 improvement on my prior constructions as disclosed in my United States Patents 1,337,944 and 1,337,945, both issued on April 20, 1920, and may be used either with or without the square operating shaft as shown 70 in these patents.

Referring more in detail to Figs. 1, 2, and 3, the mechanism consists of a plate 1 slidably mounted under rails "a" between the rail flanges and the guide bars 2 suitably 75 spaced by blocks 3 and 4. A shaft 5, centrally mounted below plate 1 and parallel to the track, is supported by bearings 6 and 7. Intermediate these bearings the shaft carries an equalizer lever 8 secured thereon 80 and connected to the arms 9 of the stops 10 by the bent connecting bars 11. Adjacent lever 8 is securely mounted another lever 12 connected by chain 13 to the arm 14 of the bell-crank-lever 15 supported by the stand 85 16 in the bottom of the trench 17. At the rear end of the shaft 5 and outwardly of bearings 7 is securely mounted lever 18 acted upon by tension springs 19 the other end of which is adjustably connected to a bracket 90 20. On the opposite end of the shaft 5 is secured the lever 21 which is connected to the tripping device 22 by means of a cable or chain 23 guided by pulley 24 mounted on support 25 secured to tie 26. 95

The shocks produced by the cars striking against the car stops 10 are absorbed by the bumper springs 27 mounted between supports 28 secured on the base 1 and the stationary supports 29 secured on tie 30. Each 100 spring is provided with a guide rod 31 secured in supports 28 and slidably mounted in supports 29. The opening of the car stops is operated by the downward motion of the elevator cage. As will be seen in the diagrams 11 and 12 the bent end 32^a of tripping member 32 will strike the nearly horizontal arm 33 of the bell-crank lever 34 rockably mounted in support 35 and cause a clockwise rotation of said bell-crank. This motion will be transmitted to the bell-crank lever 15 by the rod 37 connecting the arm 105 110

36 of the rocking lever 34 to the lower arm 38 of bell-crank lever 15 thus causing the levers to take the position shown in Fig. 12. As will be seen in this figure the levers 5 8 and 12 secured on rocking shaft 5 will be brought by a clock-wise rotation into a substantially vertical position with the result that the car stops will be opened a sufficient amount to clear the passage for the 10 car wheels, thus enabling the car to run down the suitably inclined track "a" and land on the elevator cage, where it will be retained by a special automatic stopping device which has formed the subject of a former patent of mine, and therefore need not be explicitly dealt with in this application. 15

It will be seen from Fig. 12 that after the end 32^a of tripping member 32 has passed beyond the arm 33 of bell-crank 34 the elevator cage will be permitted to travel downwardly a considerable amount without interfering with said arm. The bell-crank-lever 34 will be brought back into its normal position shown in Fig. 11 by the trigger-lever, every time it is struck by a car. 20 It will also be noted that on the return, or upward motion, of the elevator, the end 32^a will take along the bell-crank-lever 34 until the latter has described a sufficient counter 25 clock-wise movement to clear the end 32^a, as indicated by the dot and dash lines. This reversed motion will not affect the position of the car-stops; its only effect will be that of raising the arm 14 of the bell-crank-lever 15 and causing the connecting chain 13 to fold itself, as can be seen by the few dotted links shown in Fig. 12. The bell-crank lever 34 will be brought back in its 30 normal position shown in Fig. 11 by the pressure of a suitable spring, such as indicated by 45.

After the hind wheels of the first released car have passed the car-stops 10, the right hand forward wheel of the second car will 45 strike the trigger-lever 39 of the tripping device 22 and cause the lower lever 40, secured on the vertical shaft 41, rockably mounted in bearings 42 and 43 positioned on tie 44, to turn counter clock-wise. A 50 similar counter clock-wise motion will be imparted to lever 21 by the cable or chain 23 running over the guide pulley 24; thus bringing the equalizer-lever 8 back into its horizontal position, which corresponds to 55 the closed position of the car-stops, thereby arresting the motion of the second car until the tripping member 32 on the elevator cage has again acted on bell-crank 34 and correlated mechanism. The two extreme positions of lever 21 are shown by "c" and "d", Fig. 3, in which "c" corresponds to the open position of the car-stops and "d" to the closed position.

The lever 18, mounted on the forward 60 end of the rocking-shaft 5 is so connected

with spring 19 that the latter will assist the operation of the car-stops in either the closed or open position as soon as the longitudinal axis of the spring has passed beyond the center of the rocking shaft 5. When the lever 18 has reached either one of its extreme positions as shown in Fig. 8, the tension in the spring will be sufficient to hold the car-stops in their positions, thus avoiding the possibility of accidental motions which might occur if such means were not provided. 70 75

The counter clock-wise motion of the equalizer-lever 8 is limited by a stop 46 in order to prevent the spring 19 from pulling the rocker-shaft 5 beyond the horizontal position of the lever 8, thereby impossibilitating the reopening of the car-stops after the latter have been closed by the action of the trigger-lever 39. 80 85

In the Figs. 1 to 5 inclusive, I have shown the bumpers made of two springs each, the inner one coming into action only after the base plate 1, with the car-stops, have traveled a suitable distance. This construction 90 is preferable to the single spring bumper in cases where the car-stops have to resist the impact of a great number of loaded cars in motion. These figures also show the bumper springs installed inside the car 95 tracks. In Figs. 9 and 10 I have shown a modification in which the bumpers are mounted outside of the car tracks and in which the guiding rods 47 form the extension of the shaft for the rockably mounted 100 car-stops. This construction may be required in cases where the gage of the car tracks is not sufficient to permit the location of the bumpers on the inside, which is the method I prefer to use. Although I 105 have only shown spring bumpers in my drawings, I wish also to include in this application the use of any other means of absorbing shocks known to the art, but more especially the type of bumpers operating 110 with compressed air or liquids. As will be understood, the trench 17 and the bumper springs will be suitably covered to prevent accidents or exposure to the elements. 115

It is also understood that the bumpers could be so arranged as to be located in front of the base plate and car-stops instead as shown on the drawings. The position of the tripping device 22 in relation to the car stops will be determined by the size and 120 number of mine cars which are to be automatically fed to the elevator cage; the principle being that it must come into action only after the last hind wheels of the group of cars fed at one time to the cage have 125 passed the car stops.

Whenever it is desired to use the car tracks without the automatic stopping device, it is only necessary to place the car stops in their open position and to disconnect 130

nect the cable 23 from lever 40 by removing pin 40^a, which will allow the turning of the trigger 39 backward and away from the rail. The tension in spring 19 will then 5 hold the car stops permanently in their open position.

While I have illustrated and described the use of the device in connection with the approach to a mine elevator cage it is evident that this device could be used in any 10 other installation where it is desired to supply automatically one or more cars at a time, such as in any style of dump.

As will be understood, there may be slight 15 changes made in the construction and arrangement of the details of my invention without departing from the field and scope of the same and I intend to include all such variations as fall within the scope of the 20 appended claims, in this application in which I have only disclosed the preferred forms of my invention.

What I claim is:

1. In a caging device of the character described, a rockably mounted operating shaft positioned on a sliding base, car stops rockably mounted on the base supporting said operating shaft; means for operating said car stops by the operating shaft and means 30 for absorbing the shocks imposed on said car stops.

2. In a caging device of the character described, a rockably mounted operating shaft positioned on a sliding base; car stops rockably mounted on the base supporting said operating shaft; means for rocking said car stops away from the rails; car actuated means for returning said car stops into stopping position and means for absorbing the 40 shocks imposed on said car stops.

3. In a caging device of the character described, a rockably mounted operating shaft positioned on a sliding base; car stops rockably mounted adjacent to and outwardly of 45 the rails and on the base supporting said operating shaft; shaft operated means for rocking said car stops away from the rails; car actuated means for returning said car stops into stopping position; and means for 50 absorbing the shocks imposed on said car stops.

4. In a caging device of the character described, a rockably mounted operating shaft positioned on a sliding base; car stops rockably mounted adjacent to and outwardly of 55 the rails and on the base supporting said operating shaft; shaft operated means for rocking said cars away from the rails; car actuated means for returning said car stops 60 into stopping position; means for accelerating and holding said car stops into their rocked positions and means for absorbing the shocks imposed on said car stops.

5. In a caging device of the character described, a rockably mounted operating shaft

positioned on a sliding base, means for automatically actuating said operating shaft; car stops rockably mounted adjacent to and outwardly of the rails and on the base supporting said operating shaft; shaft operated 70 means for rocking said car stops away from the rails; car actuated means for returning said car stops into stopping position; spring actuated means for accelerating and holding said car stops into their rocked positions and means for absorbing the shocks imposed on said car stops.

6. In a caging device of the character described, a rockably mounted operating shaft positioned on a sliding base, cage actuated 80 means for operating said shaft; car stops rockably mounted adjacent to and outwardly of the rails and on the base supporting said operating shaft; shaft operated means for rocking said car stops away from 85 the rails; car actuated means for returning said car stops into stopping position; spring operated means for accelerating and holding said car stops into their rocked positions; means for absorbing the shocks imposed on 90 said car stops and means for guiding said sliding base.

7. In a caging device of the character described, a rockably mounted operating shaft positioned on a sliding base, cage 95 actuated means for operating said shaft; car stops rockably mounted adjacent to and outwardly of the rails and on the base supporting said operating shaft; shaft operated means for rocking said 100 car stops away from the rails; car actuated means for returning said car stops into stopping position; spring operated means for accelerating and holding said car stops into their rocked positions; means for absorbing 105 the shocks imposed on said car stops; means for guiding said sliding base and means for returning same into its initial position.

8. In a caging device of the character described, a rockably mounted operating shaft 110 positioned on a sliding base; cage actuated means for operating said shaft; car stops rockably mounted adjacent to and outwardly of the rails and on the base supporting said operating shaft; shaft operated 115 means for rocking said car stops away from the rails; car actuated means for returning said car stops into stopping position; spring operated means for accelerating and holding said car stops into their rocked positions; means for putting and holding the 120 car stops operating mechanism into inoperative position; means for absorbing the shocks imposed on said car stops; means for guiding said sliding base and means for returning same into its initial position.

9. In a caging device of the character described, a rockably mounted operating shaft positioned centrally of and parallel to the rail tracks on a sliding base; cage actuated 130

means for operating said shaft; car stops rockably mounted adjacent to and outwardly of the rails and on the base supporting said operating shaft; shaft operated means for rocking said car stops away from the rails; car actuated means for returning said car stops into stopping position; spring operated means for accelerating and holding said car stops into their rocked positions; means for putting and holding the car stops operating mechanism into inoperative position, means for absorbing the shocks imposed on said car stops; means for guiding said sliding base and means for returning 15 same into its initial position.

10. In a caging device of the character described, a rockably mounted operating shaft positioned centrally of and parallel to the rail tracks on a sliding base positioned below the rails; cage actuated means for operating said shaft; car stops rockably mounted adjacent to and outwardly of the rails and on the base supporting said operating shaft; shaft operated means for rocking 20 said car stops away from the rails; car actuated means for returning said car stops into stopping position; spring operated means for accelerating and holding said car stops into their rocked positions; means for 25 putting and holding the car stops operating mechanism into inoperative position; means for absorbing the shocks imposed on said car stops; means for guiding said sliding base and means for returning said base into 30 its initial position.

11. In a caging device of the character described, a rockably mounted operating shaft positioned centrally of and parallel to the rail tracks on a sliding base positioned below the rails; cage actuated means for operating said shaft; car stops rockably mounted on stationary shafts mounted outwardly of, adjacent and parallel to the rails and on the base supporting said operating shaft; shaft operated means for rocking said car stops away from the rails; car actuated means for returning said car stops into stopping position; spring operated means for accelerating and holding said car stops into 45 their rocked positions; means for putting and holding the car stops operating mechanism into inoperative position; means for absorbing the shocks imposed on said car stops; means for guiding said sliding base and means for returning said base into 50 its initial position.

12. In a caging device of the character described, a rockably mounted operating shaft of circular cross section, positioned centrally of and parallel to the rail tracks on a sliding base positioned below the rails; cage actuated means for operating said shaft; car stops rockably mounted on stationary shafts positioned outwardly 60 of, adjacent and parallel to the rails and on 65

the base supporting said operating shaft; shaft operated means for rocking said car stops away from the rails; car actuated means for returning said car stops into stopping position; spring operated means for accelerating and holding said car stops into their rocked positions; means for putting and holding the car stops operating mechanism into inoperative position; means for absorbing the shocks imposed on said car 70 stops; means for guiding said sliding base and means for returning said base into its initial position.

13. In a caging device of the character described, a rockably mounted operating shaft positioned centrally of and parallel to the rail tracks on a sliding base positioned below the rails; cage actuated means positioned in the rear of the car stops for operating said shaft; car stops rockably mounted on shafts positioned outwardly of, adjacent and parallel to the rails and on the base supporting said operating shaft; shaft operated means for rocking said car stops away from the rails; car actuated means, positioned ahead of the car stops, for returning said car stops into stopping position; spring operated means for accelerating and holding said car stops into their rocked positions; means for putting and holding the car stops operating mechanism into inoperative position; means for absorbing the shocks imposed on said car stops; means for guiding said sliding base and means for returning said base into its initial position.

14. In a caging device of the character described, an operating shaft positioned centrally of and parallel to the rail tracks and rockably mounted on bearings supported by a common sliding base positioned below the rails; an arm secured on said operating shaft intermediate said bearings and means for operating said lever from the cage; an equalizer lever secured on the operating shaft intermediate of said bearings and connected to arms depending from the car stops rockably mounted on stationary shafts positioned outwardly of, adjacent and parallel to the rails and on the base supporting said operating shaft; car actuated means for returning said car stops into stopping position; spring operated means for accelerating and holding said car stops into their rocked positions; means for putting and holding the car stops operating mechanism into inoperative positions; means for absorbing the shocks imposed on said car stops; means for guiding said sliding base and means for returning said base into its initial position.

15. In a caging device of the character described, an operating shaft positioned centrally of and parallel to the rail tracks and rockably mounted on bearings supported by a common sliding base positioned

- below the rails; an arm secured on said operating shaft intermediate said bearings and means for operating said lever from the cage; an equalizer lever secured on the 5 operating shaft intermediate of said bearings and connected to arms depending from the car stops rockably mounted on stationary shafts positioned outwardly of, adjacent and parallel to the rails and on the 10 base supporting said operating shaft; car actuated means for returning said car stops into stopping position; an arm secured at the rear end of said operating shaft and outwardly of the bearing, a tension spring 15 having one end outwardly attached to said arm and the other end connected to a stationary support positioned so that the longitudinal axis of the spring will cross the center of the operating shaft when said arm is rocked the full extent of its rotatable movement; means for absorbing the shocks imposed on said car stops; means for guiding said sliding base and means for returning said base into its initial position. 55
16. In a caging device of the character described, an operating shaft positioned centrally of and parallel to the rail tracks and rockably mounted in bearings supported by a common sliding base positioned below the 60 rails, supported and guided for movement longitudinally of the rails; an arm secured on said operating shaft intermediate said bearings and means for operating said lever from the cage; an equalizer lever secured on the 65 operating shaft intermediate said bearings and connected to arms depending from the car stops rockably mounted on stationary shafts positioned outwardly of, adjacent and parallel to the rails and on the base 70 supporting said operating shaft; means for arresting the counter clock-wise rotation of the operating shaft beyond the horizontal position of the equalizer lever; an arm secured at the forward end of operating shaft 75 and outwardly of the bearing and flexibly and removably connected to the car operated trigger lever; an arm secured at the rear end of said operating shaft and outwardly of the bearing; a tension spring having one end outwardly attached to said arm and the other end connected to a stationary support positioned so that the longitudinal axis of the spring will cross the center of the operating shaft when said arm is 80 rocked the full extent of its rotatable movement; bumper springs having one end supported on the sliding base and the other end carried by stationary supports and guide rods secured to the sliding base and positioned centrally of said springs, and slidably supported in the stationary supports. 85
17. In a caging device of the character described, an operating shaft positioned centrally of and parallel to the rail tracks and rockably mounted in bearings supported by a common sliding base positioned below the 90 rails, supported and guided for movement longitudinally of the rails; an arm secured on said operating shaft intermediate said bearings and means for operating said lever from the cage; an equalizer lever secured on the operating shaft intermediate said bearings and connected to arms depending from the car stops rockably mounted on stationary shafts positioned outwardly of, adjacent and parallel to the rails and on the base supporting said operating shaft; means for arresting the counter clock-wise rotation of the operating shaft beyond the horizontal position of the equalizer lever; an arm secured at the forward end of operating shaft and outwardly of the bearing and flexibly and removably connected to the car operated trigger lever; an arm secured at the rear end of said operating shaft and outwardly of the bearing; a tension spring having one end outwardly attached to said arm and the other end connected to a stationary support positioned so that the longitudinal axis of the spring will cross the center of the operating shaft when said arm is rocked the full extent of its rotatable movement; bumper springs having one end supported on the sliding base and the other end carried by stationary supports and guide rods secured to the sliding base and positioned centrally of said springs, and slidably supported in the stationary supports. 95

In testimony whereof I affix my signature.
JAMES A. NOLAN.
